UNITED STATES PATENT OFFICE.

MICHAEL F. MCMAHON, OF WORCESTER, MASSACHUSETTS.

FRICITION-CLUTCH.

SPECIFICATION forming part of Letters Patent No. 712,575, dated November 4, 1902.

Application filed February 27, 1902. Serial No. 96,030. (No model.)

To all whom it may concern:

Be it known that I, MICHAEL F. MCMAHON, a citizen of the United States, residing at Worcester, in the county of Worcester and 5 State of Massachusetts, have invented new and useful Improvements in Friction-Clutches, of which the following, together with the accompanying drawings, is a specification sufficiently full, clear, and exact to enable persons skilled in the art to which this invention appertains to make and use the same.

My present invention relates to certain features of improvement in the construction and organization of clutch mechanism applicable 15 to that class of friction grip-clutches example of which is set forth and described in the Letters Patent No. 520,447, dated May 29, 1894, heretofore granted to me.

The chief objects of my present invention 20 are to provide facilities for accommodating endwise variations caused by expansions in the shafting without affecting the operating relation of the inner disk with respect to the clutch-plates, to provide a dual-arranged 25 draw-rod-actuating system of improved structure and combination, and to render the clutch more efficient, desirable, and convenient for use and in meeting the various conditions of practice. I attain these objects by mechanism 30 of the character described in the following detailed description, the particular features of improvement and subject-matter claimed being hereinafter definitely specified.

An embodiment of my invention is illustrated in the accompanying drawings, where- 35 in—

Figure 1 is a central longitudinal section view showing the clutch as when closed, the upper portion being a side view. Fig. 1^a is 40 a separate view of the link-joint stop. Fig. 1^b is a line diagram illustrating the action or movement of the yoke-lever, draw-rods, and operator-link in the opening or closing of the clutch. Fig. 2 is a top view of the clutch as 45 when open or released. Fig. 3 is a side view of the disk-carrying hub. Fig. 4 represents an end view of the clutch looking toward the front plate. Fig. 5 is a front view of the yoke or transverse bar of the yoke-lever, showing 50 the draw-rod seats. Fig. 6 is a view of said bar, showing the draw-rod nuts and guard-spring. Fig. 7 is a view of the inner disk, showing the jaw members which connect the

disk and its carrying-hub in transverse section. Fig. 8 shows an end view of the disk-carrying hub. Fig. 9 shows the form of the eye or central opening in the disk, and Fig. 10 shows a side and end view of the internal shaft-bushing ring.

On the drawings the reference-numerals 1 and 2 indicate the shafts, which are herein termed the "primary" and "secondary" shafts, the former being preferably and in this description considered as the driver and the latter as the driven member, although in practice the clutch mechanism is fully operative for transmission of power and motion in either direction or from either shaft to the other.

The body of the clutch comprises a front 70 plate 3 and back plate 4, having inner pressing-faces and oppositely-projecting rims that engage with each other by a series of indentations or means that cause the two plates to rotate in unison, while permitting endwise 75 retraction and approach of the plates for gripping the disk in well-known manner. The hub of the front plate is fixed or keyed upon the shaft 2. The back plate 4 is of annular form with open center and is carried by its 80 rim concentric with the axis. The friction-disk 5 occupies a position intermediate to the front plate and back plate, and annular pads 6 and 7, of vulcanized fiber or other suitable friction material, are disposed between the 85 respective faces of the disk and pressure-faces of the clutch-plates, as illustrated in Fig. 1.

In accordance with my invention a disk-carrying hub 8 is keyed or fixed upon the primary shaft 1, and said hub is provided at 90 its end with a series of longitudinal recesses or jaws 9 and alternate lugs or detents 10, while the center of the disk 5 is provided with an eye or opening 11, having jaw-recesses 12 and projecting lugs or detents 13, adapted for interlocking with the jaw members or detents upon the end of the hub, which is inserted endwise through the eye 11 of the disk, extending completely through or beyond the same, so that the disk is supported concentric and 100 non-rotative upon the hub, while the hub can have endwise movement in the eye of the disk without disturbing their rotative relation. The endwise variations or expansion or contraction of the shafts is thereby accommodated without injuriously affecting the rela- 105

tion of the disk and clutch-plates or the perfect operation of the clutch.

The end of the hub 8 is made hollow or with a tubular bearing-cavity 14, into which the 5 end of the secondary shaft 2 extends and is supported. (See Fig. 1.) Between the interior surface of the hub and the shaft I preferably arrange antifrictional bushing or bronze rings 15, (see Figs. 1, 7, and 10,) fitted to rotate 10 free and independent of both the shaft and bearing-surfaces, so as to move or lie idle in respect to either surface. Said intermediate bushing is preferably made as a plurality of separate ring-sections—two are shown in the 15 present instance—and said rings are best perforated radially with a number of holes for taking up and carrying oil. In any instance, if so desired, the rings 15 may be omitted and the bearing formed by the interior hub- 20 surface directly upon the shaft 2.

The draw-rods 16 for closing the clutch are in my present invention arranged to work in dual order or coupled in pairs by means of yoke-levers 17 in the manner illustrated, which 25 is essentially as follows: The front plate 3 is provided at or near its periphery with integral or rigid projecting ears 18, and the yoke-lever 17 is made with a pair of hinging-ears, between which the plate-ear 18 is received and the lever 30 pivoted thereto by a transversely-disposed pin 19. This forms the fulcrum-axis of the yoke-lever. The ends of the yoke extend laterally right and left beyond the respective hinging-ears and are adapted for the connection therewith of the draw-rods 16 at points 35 20, somewhat forward of the plane of the pivoting-axis 19. This connection is preferably made by circular concaved seats 21, in which the adjusting-nuts 22 of the draw-rods are 40 respectively seated, said nuts being shaped with a convex or spherical bed-surface matching said seat, and the opening 23 in the yoke-lever for carrying the draw-rods being formed of a funnel shape and oblong cross-section 45 to permit a relative rocking action of the yoke-lever without cramping the draw-rods.

The draw-rods are best made with T-heads 24, having rounded under surfaces that rest in transverse bearings or concaved seats 25 on the back of the clutch-plate 4, which is provided with bosses 26, having funnel-shaped openings through which the draw-rods extend. The clutch-plates are fitted with suitable openings or peripheral recesses 27 (see Fig. 2) to 50 accommodate the draw-rods and to give space for their limited swing movement when the clutch is operated.

The yoke-levers 17 each have a projecting arm disposed at central position on the double-ended yoke-bar, and the bifurcated swinging ends of said arms are pivotally connected at 55 28 with the spreaders or links 29, the opposite ends of said links being pivotally joined at 30 with the shifter-sleeve 31, mounted 60 upon the shaft 2 and movable thereon in well-known manner for controlling the action of the clutch.

The end of the link 29 is best formed with a lug or protuberant angle 32, which abuts against the shoulder of the yoke-lever arm at 70 the joint 28 (see Fig. 1^a) and acts as a stop for the release movement of the clutch when the sleeve 31 is moved outward, bringing the links and yoke-levers to the positions indicated by dotted lines *o* on Fig. 1, which corresponds with the idle or unclutched position 75 of the mechanism.

When the strain on the draw-rods is relieved, the clutch-plates 3 and 4 are pressed outward from the disk 5 and held apart by 80 springs 33, arranged in recesses formed in the rims of the clutch-plates, said springs acting by expanding tension between the opposite rims, as indicated in Fig. 1.

In the present instance a clutch having two 85 yoke-levers and pairs of draw-rods is shown; but it will be understood that in practice these clutches may be made with two, three, four, or six yoke-levers and pairs of draw-rods, more or less, as desired, according to the 90 size or diameter of the clutch-plates required for transmission of the power in any particular situation, the several pairs of draw-rods and sets of double-end yoke-levers and connecting-links being arranged in the manner 95 above described and in radial relation to the axial shaft and slidably sleeve.

Combined with the draw-rods and their actuating and adjusting devices I employ a spring device for indicating adjustment and 100 retaining the nuts 22 at position of adjustment. Said spring device is best shown in Fig. 6 and consists of a spring or resilient wire 35, secured to the metal or arm between the draw-rods or intermediately adjacent thereto, 105 with its ends extending outward and arranged to press with spring force against the flat sides of the nuts 22 at either side thereof. When adjusting the grip tension of the clutch, uniformity of adjustment at the several draw-rods is readily attained, since the springs 35 110 serve as gages for each one-sixth revolution of the nuts, and the operator can thus calculate accurately by moving the nuts on all of the rods an equal number of sixths, the flex 115 of the respective springs being a true guide therefor. The springs also serve for keeping the nuts at their adjusted positions. The ends of the springs may extend directly outward, as shown, or may be bent upward to 120 rest against the flat of the nuts at any desired angle or at any side thereof. In the present instance the spring-wire is secured in a hole formed through the yoke-lever arm; but any other suitable manner of securing the wire 125 can be employed, if desired.

In the operation the link 29, yoke-lever 17, and draw-rods 16 act as a dual toggle-joint system, the joints 30 and 20 being brought into straight alinement with directions of 130 strain when closing the clutch-plates upon the disk 5, thus giving a firm unyielding grip thereon when set and releasing readily when the toggles are swung off their central

alinement by the outward movement of the shipper-sleeve. The action is illustrated by the diagram Fig. 1^b, wherein the full lines indicate the position when the clutch is on or closed and the dotted lines indicate the position when the clutch is off or open, the swing of the point 20 giving the amount of movement of the clutch-plate 4 for the friction-release, as indicated at 40.

10. What I claim, and desire to secure by Letters Patent, is—

1. In a friction grip-clutch, comprising frictional-faced front and back clutch-plates, and means for closing and releasing said 15 clutch-plates upon a disk; the primary-shaft disk-carrying hub fixed upon the primary shaft and provided at its end with jaw recesses and lugs, in combination with the friction-disk mounted upon said hub and 20 provided with jaw recesses and lugs interlocking those on the hub.

2. In a friction-clutch, in combination with the primary and secondary shafts, front and back friction clutch-plates, inner friction-disk, and means for closing and releasing said 25 clutch-plates; the disk-carrying hub adapted to extend completely through the inner friction-disk mounted upon said hub, the hub and disk being rotatively united by 30 interlocking members that permit endwise variation in the relative positions of the hub and disk without affecting the rotative relation of said parts.

3. In a friction grip-clutch mechanism, the 35 disk-carrying hub secured upon the primary shaft, and having its end provided with a bearing-opening for receiving the end of the secondary shaft, said hub externally formed with longitudinal jaw recesses and lugs, the 40 friction-disk concentrically supported upon said hub and non-rotatively intermeshing therewith by recesses and lugs at its central eye, but free for endwise movement thereon; in combination with the primary and secondary shafts, the main clutch-plate secured 45 upon said secondary shaft, the annular clutch-plate interlockingly engaging said main clutch-plate, and means substantially as described, for opening and closing the 50 clutch-plates for embracing and releasing the disk.

4. A yoke-lever comprising the double-end transverse yoke-bar, each end thereof provided with a hole and concave seat for connecting and straining a draw-rod, also provided with projecting fulcrum-hinging ears out from the line of said yoke-bar, and the operating-arm integrally formed with, and projecting centrally from said yoke-bar; in 55 combination with the interposed friction-disk, the clutch-plates, one of which is provided with a rigidly-attached hinge-ear, the fulcrum pivot-pin arranged through said hinging-ears, the pair of draw-rods having 60 the bosses or nuts resting in said seats, and means for actuating said yoke-lever, substantially as set forth.

5. In combination, with the friction-disk and clutch-plates, the main clutch-plate provided with a rigid projection or ear-lug; a 70 rod-straining toggle or yoke-lever having dual rod-holding points, and provided with intermediate hinging-ears, the fulcrum-pin pivotally connecting said yoke-lever to the clutch-plate ear, the fulcrum-axis being at some distance rearward from the plane of said rod-holding points, the draw-rods arranged in pairs connecting the back clutch-plate with the respective wings of said yoke-lever, the endwise-movable shipper-sleeve, and a toggle-link connecting the arm of said yoke-lever with said sleeve. 75

6. In combination with the friction-disk and clutch-plates oppositely embracing said disk, the main clutch-plate provided with a 80 projection or ear-lug; the actuating-toggle or yoke-lever comprising an arm and transverse yoke-bar having ears pivotally fulcrumed to the ear-lug on said clutch-plate, said yoke-lever having openings therein for receiving the 85 draw-rods, and provided with concaved seats that form holding-points for straining said rods, a pair of draw-rods connecting the back clutch-plate and yoke-lever, said rods having rounded heads that rest in suitable bearings 90 on the back plate, adjusting-nuts threaded on said rods and supported in said concaved seats on the yoke-lever; and a shipper-controlled means for rocking said yoke-lever to simultaneously strain or relieve the pair of 95 draw-rods. 100

7. In a friction-clutch, the combination, with the shipper-sleeve, clutch-plates, the friction-disk, draw-rod, and draw-rod-actuating lever provided with a shoulder; of a toggle-link connecting said sleeve and lever, and having the protuberant end 32 adapted for abutting against the shoulder on said actuating-lever for limiting the retractive movement of the sleeve and rod-actuating levers, 105 substantially as set forth.

8. The combination with the primary and secondary shafts, the clutch-plates carried and secured on said secondary shaft, and means for operating the clutch-plates, as described; of the disk-carrying hub fixed on the primary shaft, and having the internal shaft-receiving hollow and external jaw recesses and lugs, the inner friction-disk embraced between the clutch-plate faces, and movably 110 mounted on said hub, said friction-disk having jaw recesses and lugs that rotatively interlock with those on said hub, and the perforated unattached antifriction-rings disposed around the end of the secondary shaft within 115 the hollow of said hub, all substantially as and for the purpose set forth.

Witness my hand this 25th day of February, 1902.

MICHAEL F. MCMAHON.
